UNITED STATES PATENT OFFICE.

HERMAN A. AGRICOLA, JR., OF ATLANTA, GEORGIA, ASSIGNOR TO MERTHALER LINOTYPE COMPANY, A CORPORATION OF NEW YORK.

TYPOGRAPHIC MACHINE.

SPECIFICATION forming part of Letters Patent No. 789,646, dated May 9, 1905.

Application filed October 23, 1903. Serial No. 178,253.

To all whom it may concern:

Be it known that I, HERMAN A. AGRICOLA, Jr., of Atlanta, county of Fulton, and State of Georgia, have invented a new and useful Improvement in Typographic Machines, of which the following is a specification.

My invention relates to linotype-machines wherein independent circulating matrices are stored in a magazine, from which they are delivered singly at the lower end, assembled in lines, and presented to a slug-casting mechanism and thereafter transferred to a distributing mechanism, by which the matrices are delivered into the upper ends of the proper magazine-channels.

The aim of the invention is to adapt the machine to carry two or more fonts or sets of matrices in such manner that either one may be brought into action at will.

To this end it consists in the employment of a pivoted multiple magazine comprising two or more single magazines or sections, each adapted to carry a font or series of matrices, in combination with a single distributing mechanism.

It also consists in the combination, with the multiple magazine, of devices for operating the matrix-delivering escapements of that section which is for the time being in operative position.

It also consists in an automatically - controlled font-distinguisher to prevent the matrices from entering the wrong magazine-sections.

It also consists in various minor details, which will be hereinafter described.

Referring to the drawings, Figure 1 is a longitudinal vertical section through a magazine, distributing mechanism, and attendant parts constructed in accordance with my invention, the middle portion of the magazine being broken away to reduce the size of the figure. Fig. 2 is a similar view showing the parts in outline, on a smaller scale, with the magazine adjusted to a different position.

Fig. 3 is a perspective view illustrating a detail of the escapement - operating devices. Fig. 4 is a longitudinal vertical section simi-

lar to Fig. 1, except that the magazine is shown in the upper instead of the lower position. Fig. 5 is an end view of a portion of the distributing mechanism, showing the automatically - adjustable font - distinguisher. Fig. 6 is a perspective view of the distinguisher. Fig. 7 is a perspective view of a portion of the upper end of the magazine, illustrating details of construction. Fig. 8 is a side elevation of parts shown in the preceding figure in different position and the distributor-bar and feed-screws in section. Fig. 9 is a view looking against the lower end of the magazine, illustrating details of the escapement-operating devices. Fig. 10 is a diagram illustrating a preferred arrangement of the parts for operating the escapements.

Referring to the drawings, A represents a multiple magazine consisting in the present instance of two sections, chambers, or single magazines a' , one overlying the other and each adapted to carry a font or series of matrices. The sections are firmly secured to each other and to a supporting-frame a^2 , which is mounted near its lower end on a horizontal rod or pivot a^3 , sustained in the rigid main frame B. The dual magazine is free to swing upward and downward at its upper end in order that either the upper or lower section or chamber may be brought into operative relation to the distributing devices.

The lower ends of both magazine-sections deliver their matrices into a vertically-channeled throat or guideway W, fixed to the main frame and serving to guide the matrices downward to the line-assembling mechanism, which may be of the ordinary or of any other suitable construction. The throat W differs from that in use in the commercial linotype-machine mainly in that it is widened vertically at the upper end, so that, although fixed in position, it will receive and guide the matrices from both sections of the magazine, the lower end of which remains in practically the same position at all times.

It will be observed that, owing to the location of the horizontal pivot near the lower end of the magazine and remote from the up-

per or receiving end, the magazine may be shifted sufficiently to place one section or the other in operative—that is to say, receiving—relation to the distributer, while the lower end remains in operative relation to the escapement-actuating and matrix-receiving devices.

The horizontal pivot serves as a guide to prevent the magazine from shifting either longitudinally or laterally out of position. It insures the proper location of the magazine in reference to the other parts when in both positions, and it avoids the need of the expensive and troublesome guides which would be necessary to control the magazine were it mounted to rise and fall bodily.

The magazine may be of any ordinary or suitable construction. In the form shown each section consists of two separated parallel plates grooved in their opposing faces to receive and guide edges of the matrices, as in the standard Mergenthaler machines.

The upper end of the magazine rests upon and is supported by eccentrics C on a rock-shaft D, mounted in the main frame and provided with an operating-crank E, by means of which the eccentrics may be turned so as to lower the magazine to the position shown in Fig. 1 or raise it to the position shown in Fig. 2.

F represents a horizontal distributer-bar of the ordinary Mergenthaler type toothed in its lower edge and located above the upper end of the magazine.

G G' G² are the usual feed-screws, lying adjacent to the distributer-bar, for the purpose of carrying the toothed matrices H, held in suspension by the teeth on the bar, along the latter until they arrive over their appropriate channels in the magazine.

I is a stationary throat or entrance for guiding the matrices which fall from the distributer-bar into the magazine-channels, as in the commercial Mergenthaler machines. This throat or entrance I is provided with the usual upright partitions, between which the matrices are guided in their descent and maintained on edge.

When the magazine is in its lower position, (shown in Fig. 1,) the upper section or chamber will stand in alinement with the throat I and the matrices will be delivered from the distributer into the upper chamber or section a. When, on the other hand, the upper end of the magazine is raised to the position shown in Fig. 2, the matrices will be delivered into the lower chamber or section a'.

It will be observed that by simply swinging the upper end of the magazine a single distributing mechanism is made available for delivering the different fonts or sets of matrices into the respective chambers of the magazine.

While the eccentrics herein shown are effective for the purpose of adjusting and support-

ing the end of the magazine, it is to be understood that they may be replaced by any equivalent devices.

For the purpose of controlling the delivery of the matrices from the magazine-channels I provide each chamber or section of the magazine for each channel therein with an escapement K, consisting of a centrally-pivoted lever, carrying at opposite ends pawls or dogs k k, which are alternately projected into the magazine as the lever is vibrated. This device is essentially the same as that used in the Mergenthaler linotype, differing only in details hereinafter recited. The lower section of the magazine has its escapements on the under side, while those of the upper section are on its upper side, as shown in the several figures.

Each escapement-lever is acted upon by a spring k², which tends to hold the lower pawl 85 within the magazine, that it may retain the terminal matrix therein. The vibration of the escapement-levers causes the alternately-acting pawls to release the matrices one at a time, the second matrix immediately assuming position at the extreme end of the magazine in place of the one discharged.

For the purpose of operating the escapements of that magazine-section which is for the time in action I propose to use in connection with any ordinary keyboard mechanism a single series of rods or actuating devices adapted for connection with one set of escapements or the other. These devices may be made in a great variety of equivalent forms. 95

As the escapements are mounted in and carried with the magazine, the latter may be made of the usual full length to carry a full font or complement of matrices, which are held wholly within the magazine, so that it may be 105 adjusted at any moment and change thus made from one set of matrices to another.

In Figs. 1, 2, and 4, M represents vertically-reciprocating rods guided in the main frame and connected with the finger-keys or equivalent operating devices in any suitable manner. Each of these rods is forked at the top, one end, m, being in position to act upon the escapements of the lower magazine-section when the latter is in operative position, 115 as shown in Fig. 4, while the other end, m', is in position to act on the lower end of a vertical slide or link m², seated in a slot in the end of the magazine and acting at its upper end on an escapement-lever of the upper magazine, as shown in Fig. 1.

The rocking or tipping movement of the entire magazine around the pivot a³ establishes an operative connection with one arm or the other of the actuating-rod M, the connections being automatically changed as the magazine is shifted.

The slides m² for operating the upper escapements are thin strips of metal. They are seated in grooves or slots in the magazine be- 130

tween the paths of the outgoing matrices, as shown in detail in Figs. 3 and 9, their upper ends being carried laterally to engage the escapement-levers. These slides are preferably slotted, as shown in Fig. 3, and secured in position by transverse pins m^4 ; but they may be made in any equivalent form and held in position by any suitable means, the essence of the invention in this regard lying in the extension of operating means from an escapement at one side of a magazine, through the magazine, to its opposite side.

Fig. 10 illustrates another automatic arrangement for shifting the connection for operating the escapements. In this case the operating-rods M from the keyboard, having a single upper end, are passed through a horizontally-movable guide-plate m^5 , by which they may be shifted forward and backward, so as to act upon the lower escapements, as shown in full lines, or upon the slide m^2 for operating the upper escapements, as indicated in dotted lines. The shifting of the guide-plate m^5 may be effected by any suitable means. In the drawings I have provided an automatic mechanism consisting of a horizontal rock-shaft m^6 , mounted in the main frame and provided with depending arms m^7 , engaging the guide-plate, and with an arm m^8 , bearing on the under side of the magazine. A spring m^9 tends to carry the plate forward and establish connections with the upper escapements when the upper section of the magazine is in use. When the rear end of the magazine is raised to bring the lower section into action, the lower end swinging downward depresses the arm m^8 , causing the guide-plate m^5 to be moved rearward, so that connection will be established with the lower escapements.

Both the upper and the lower magazine-sections will deliver their matrices into stationary front channeled guide or race plates, by which they will be delivered to an assembling mechanism, such as that used in the Mergenthaler linotype, or to any equivalent mechanism for arranging the matrices in a common line.

It is customary in linotype-machines to provide the matrices of each font with a font-distinguishing notch in the lower end in a position peculiar to that font. It is also usual to provide in advance of the distributer-bar an adjustable font-distinguishing pin, standing in such position as to pass through the slots in the lower ends of the advancing matrices. If a matrix of a different font, having its notch in a different position, accidentally enters the machine, it will be arrested by the pin and held until removed by the attendant.

In the present machine, carrying two fonts of matrices, it is desirable to provide for the automatic adjustment of the font - distinguisher so that when either magazine is brought into action the distinguisher will be

properly set to permit the passage of the matrices belonging in said magazine, and no others. My device for this purpose is shown in Figs. 5 and 6. The matrices for the upper magazine are constructed, as shown, with two notches in their lower end, while those for the lower magazine have but a single notch. I mount below and in advance of the distributer bar the distinguishing-pin O , preferably carried, as usual, on a horizontally-threaded slide, having at one end a nut o , by which it may be adjusted endwise to set the pin in position to pass through one slot in matrices for either magazine. Adjacent to this pin I mount a second distinguishing-pin O' , arranged to slide vertically and connected by a lever o^2 with a rod o^3 , carried downward and having at the lower end a toe o^4 , underlying the magazine. A spring o^5 , Fig. 6, acting on the lever o^2 , tends to draw the distinguisher O' downward to an inactive position below the path of the matrices.

When the upper magazine-section is in action, the two distinguishing-pins are in operative position, as shown in Fig. 6, and only those matrices which contain two notches are permitted to enter the magazine. When, however, the lower magazine-section is in action, the pin O' is permitted to fall and matrices containing a single distinguishing-notch are permitted to enter the magazine.

The upper end of the magazine and the lower end of the stationary throat or entrance are so formed and arranged in relation to each other that a close joint is secured between them in both positions of the magazine. In order, however, to insure a very close joint and to prevent the possible existence of an opening or the possible failure of alinement, such as would interfere with the free passage of the matrices into the magazine, I propose to give the throat or entrance or its guiding surfaces a slight motion to and from the end of the magazine and to effect a slight but automatic separation during the movement of the magazine and the automatic closing together of the parts after the adjustment is completed. These results may be variously attained; but I have represented in the drawings a construction which I consider satisfactory.

Referring to Figs. 1 and 8, it will be seen that the throat is provided on its under side with guiding-lips i , engaged over corresponding shoulders on the main frame in such manner as to allow a slight longitudinal movement of the throat to and from the end of the magazine. On the side of the throat there is secured an arm i^2 , resting at its end against a notched plate i^3 on the magazine. As the magazine moves up or down, carrying with it the notched plate, the arm i^2 is compelled to ride out of the notch and move backward, carrying with it the throat I . Whenever the magazine reaches its limit of movement in

either direction, the arm t^2 enters a notch and the throat moves forward, so as to form a close joint with the magazine. A spring t^4 may be extended, as shown, from the frame 5 to the throat in order to pull the latter forward snugly against the end of the magazine.

As an additional means of securing the adjustment of the upper end of the magazine to the exact position required, I propose to use an 10 alining and locking plate T, the ends of which are arranged to slide in guiding-slots t in the main frame, as shown in Fig. 8, so that the lower edge of the plate which overlies the throat or entrance for the matrices may be 15 moved to and from the end of the magazine. To the outer ends of the plate are secured arms t^3 , the ends of which ride against the notched plate t^2 , before referred to. The lower edge of this plate T should be given a 20 rounded or V form in cross-section to enter corresponding grooves in the end of the matrix or otherwise formed to interlock therewith.

When the magazine is moved either up 25 ward or downward, the plate t^3 forces the arms t^2 and plate T upward, so that the plate is disengaged from the magazine as the latter begins to move and reengaged therewith as the movement is completed. Springs t^5 are 30 applied to urge the plate T downward.

In order to close the upper exposed end of the upper magazine-section when it is not in use, I provide a rising and falling gate P, hinged thereto or otherwise supported. When 35 the magazine falls, as shown in Fig. 1, the upper free edge of this gate is turned upward by the plate p , and when the magazine rises the gate is permitted to fall.

While I have represented the magazine here- 40 in as arranged in an inclined position, it is to be understood that this is not of the essence of the invention and that it may be arranged in an upright position, if preferred.

The form of the distributor and the throat 45 or entrance plate for directing the matrices into the magazine are not of the essence of the invention, and they may be modified at will. In other words, any form of distributor may be employed.

50 I believe myself to be the first to mount a magazine having a plurality of chambers or sections so that it may be vibrated at the receiving end without materially disturbing the position of the delivery end. I also believe 55 myself to be the first to combine with a single distributing mechanism a vibratory multiple magazine either section of which may be brought into action at will and a single throat or raceway for receiving the matrices from 60 the magazine and directing them to the assembling mechanism.

Having thus described my invention, what I claim is—

65 1. In a typographic machine, the combina- 130 tion of a distributor and a multiple magazine

hinged at a point remote from its receiving end, whereby the receiving end is permitted to vibrate in relation to the distributor, in order that the latter may deliver the matrices to one chamber or another of the magazine, 70 as required without destroying the operative relation of the lower end to the coöperating parts of the machine.

2. In a typographic machine, a multiple magazine mounted to turn about an axis near 75 its delivery end, substantially as and for the purpose specified, whereby adjustment of the receiving end in relation to the distributing mechanism is permitted, without disturbing the operative position of the delivery end. 80

3. In a typographic machine, a multiple magazine pivotally supported, in combination with means for turning the same to and fro about the pivot to predetermined positions to bring one magazine-section or another into 85 action.

4. The multiple inclined magazine mounted on a pivotal support remote from the distributor, in combination with a fixed distributor, 90 a throat or guide adapted to receive matrices from both magazines, and means for moving the magazine about its pivot, to bring one section or another in operative relation to the distributor, whereby the upper end of the magazine may be adjusted to receive matrices in 95 either section at will, without disturbing the operative position of the delivery end.

5. In a typographic machine, the dual pivoted magazine, a single distributor, means for moving the magazine to bring one section or 100 another in communication with the distributor, escapements at the top and bottom of the respective magazine-sections, and means for operating one series of escapements or the other, according to the position of the magazine. 105

6. In a typographic machine, a multiple pivoted magazine in combination with a single distributor to coöperate therewith, and a single guide or channel plate to receive the matrices from the magazine. 110

7. In a typographic machine, two parallel magazine chambers, two series of escapements located in the outermost sides of the respective magazines, operating connections extended through the magazines from one set of escapements to the other, and means for preventing the action of either set of escapements at will. 115

8. In a typographic machine, a magazine, 120 an escapement mounted on one side thereof, and an actuating-slide extended through the magazine between the paths of the matrices, with one end turned laterally to engage and actuate the escapement. 125

9. In combination with a magazine having escapements on one side and slots in its end, escapement-actuating slides seated in said slots between the matrix-paths.

10. A dual - pivoted vibratable magazine, 130

provided at one end with two series of escapements for its respective chambers or sections, and escapement-operating devices arranged to connect with one series of escapements or the other, according to the pivotal position of the magazine.

11. In a typographic machine, a magazine having a plurality of chambers or sections, a series of escapements for each section, a single series of actuating-rods, and means for shifting said rods into operative connection with one series of escapements or another, as required.

12. In a typographic machine, a multiple magazine mounted to turn about a transverse axis between its ends, whereby the opposite ends are caused to move in reverse directions, in combination with means for delivering matrices thereto at one end and means for receiving the released matrices from the opposite end.

13. In combination with the multiple movable magazine, the interlocking plate T, movable to and from the end of the magazine, and means for effecting the movement of said plate.

14. In combination with the multiple movable magazine, the interlocking plate, movable to and from the end of the magazine, and automatic means for effecting the movement of said plate.

15. In a typographic machine, the combination of a movable magazine and a throat or guideway for the incoming matrices, movable lengthwise of the magazine and adapted to in-

terlock with the latter in its different positions, whereby a close union between the two is insured.

16. In a typographic machine, the combination of a multiple movable magazine, a throat or guideway for the incoming matrices, 40 and automatic means for separating the throat from the magazine during the adjustment of the latter, and returning it thereto.

17. In a typographic machine, a pivoted swinging magazine and throat or guideway 45 movable to and from the magazine, in combination with the arm τ^2 and plate τ^3 , controlling the position of the throat.

18. In a typographic machine, a multiple movable magazine, in combination with an 50 automatic gate, closing the upper end of the section or chamber which is not in use.

19. In a typographic machine having a plurality of magazine-chambers, two independently-adjustable font-distinguisher. 55

20. In a typographic machine having a plurality of magazine-chambers, a font-distinguisher, O, adjustable transversely of the path of the matrices, and a second distinguisher, O', adjustable at right angles to the line of 60 movement of the first.

In testimony whereof I hereunto set my hand, this 19th day of October, 1903, in the presence of two attesting witnesses.

H. A. AGRICOLA, JR.
